UNITED STATES PATENT OFFICE.

JOHN A. CRAIG, OF LAUDERDALE, MISSISSIPPI.

CAR-COUPING.

SPECIFICATION forming part of Letters Patent No. 315,602, dated April 14, 1885.

Application filed July 25, 1884. (No model.)

To all whom it may concern:

Be it known that I, JOHN A. CRAIG, of Lauderdale, in the county of Lauderdale and State of Mississippi, have invented a new and 5 useful Improvement in Car-Couplings, of which the following is a full, clear, and exact description, reference being had to the annexed drawings, forming part thereof.

This invention relates to improvements 10 whereby ordinary pin-and-link couplings may be coupled automatically.

In the drawings, Figure 1 is a side elevation of part of a car. Fig. 2 is a vertical section of part of another car in position for 15 coupling with the first, and Fig. 3 is a cross-section of the draw-head.

A indicates the draw-head, and B is a pend- 20 ent link-lifter formed by bending a rod about the draw-head and turning its ends C up through perforations C in the bottom of the draw-head. The weight of the lifter resting 25 on top of the draw-head causes the ends C to lie below the chamber of the draw-head out of the way of the entering link; but when the link is coupled with the draw-head its outer 30 end is to be lifted for coupling with another car by lifting the device B and causing its ends C to bear up against the link. For this pur- 35 pose a rod, D, is connected to the lifter and extended to the top of the car, where it is held in a support, E. This support is pro- 40 vided with a series of shoulders, F, of differ- 45 ent elevations, arranged around the opening in the support E in which the rod D works,

and the upper end of the rod, being bent to 35 form a handle, also forms a shoulder, G, by which the rod may be supported on any one of the shoulders F, according to the height of the coupler with which the link is to be coupled. The jarring of the cars in coupling will 40 cause the rod D to drop and release the link. The pin H is supported in a yoke, I, secured to the upper part of the draw-head, and a lifting-rod, J, is attached to the pin near its middle, and supported in a perforation in the sup- 45 port E. The pin is supported in a raised po- 50 sition by a spring-bumper, K, arranged in the draw-head. When the pin is lifted, the bumper is pressed outward by its spring in position for forming a rest for the pin, and when the 55 entering link presses the bumper back the pin falls and engages the link. The pin may be supported by a shoulder on the rod J, adapted to engage the support E, if preferred.

What I claim is—

In a car-coupling, the combination, with the 55 draw-head A, of the link-lifter consisting of the bail-shaped rod B, with its side portions curved or extended at their lower ends for- 60 wardly and inwardly, said latter portions hav- 65 ing upwardly-extended portions C, projecting up into the link passage or chamber, substan- tially as shown and described, and for the pur- 70 pose set forth.

JOHN A. CRAIG.
